Charles J. Shepard
Design for Stove
Patented July 4, 1862

Charles J. Shepard
Wm. & Wm. E. Borden
John T. Davidson

UNITED STATES PATENT OFFICE.

CHARLES J. SHEPARD, OF NEW YORK, N. Y.

DESIGN FOR A STOVE.

Specification forming part of Design No. 1,523, dated February 4, 1862.

To all whom it may concern:

Be it known that I, CHARLES J. SHEPARD, of New York, in the county and State of New York, have produced a new and original Design for Stoves; and I do hereby declare that the following is a full and exact description of the same, reference being had to the accompanying drawings, and to the letters of reference marked thereon.

The nature of my invention consists in the design and configuration of a stove in the shape of an acorn placed upon a base forming the ash-pit of the stove.

Figure I represents an outside front view of my design of a stove. Fig. II shows a longitudinal section of the same. Fig. III shows a horizontal section. Fig. IV shows the design of the ornamented outside covering-plate on a larger scale.

The upper parts A and B, forming, when fastened together, the stove, are made in the form and shape of an acorn with corrugated surfaces. The forward part C of the ash-pit is made circular, to form a base for the acorn-shaped stove to rest upon.

The plate L on the forward part A of the stove is ornamented on the front side with diagonal lines crossing each other, so as to form small squares or diamonds, in the center of which small dots or spots may be placed. This plate L covers the flange a, which fastens the after part B to the forward part A, and covers likewise all the tubes and smoke-pipes at the back. The forward part A is then again covered by a perforated plate M, likewise in the shape of an acorn and corre-

sponding nearly with the shape of the forward part A. This plate M rests upon the base or ash-pit C, and is fastened against the plate L and provided with a suitable opening for the box D and fire-doors to pass through. This plate M is made of bent bars x, running diagonally and circular over the surface and bent in wave-lines crossing each other, so as to form diamonds. Within these diamonds small crosses w are again arranged to reduce the openings, and the spaces between these crosses w and the bars x are left open and form the perforations through the plate M. The sides of the hole in this plate M, through which the box D and the fire-doors project, are further ornamented with small scroll-work s, and the top of said plate is finished with a circle of radiating leaves. (See Fig. I.)

The stove is placed into a fire-place, and a mantel grate-frame W of any desired pattern placed in front around the plate L, by which said frame W the opening of the fireplace or mantel is filled up in the usual manner, and showing then only the one-half or forward part A of the stove covered with the ornamental perforated plate M of an acorn shape, resting upon a circular ash-pit box, as represented in Fig. I.

What I claim as my invention, and desire to secure by Letters Patent, is—

The peculiar form and figure herein described and set forth as the design for a stove.

CHARLES J. SHEPARD.
